(57) **CLAIM**

The ornamental design for a shirt, as shown and described.

DESCRIPTION

FIG. 1 is a front view of a shirt, showing the new design; FIG. 2 is a rear view of the shirt shown in FIG. 1; FIG. 3 is a zoomed-in view of patterns shown in FIG. 2; and, FIG. 4 is a zoomed-in view of patterns shown in FIG. 1. The broken lines represent the portions of the shirt that form no part of the claimed design. The word “IntelliSkin” shown in broken lines in FIG. 2 forms no part of the claimed design. The shaded areas in FIGS. 1 and 2 indicate patterns that are printed on an inside of the shirt. In particular, the patterns shown in FIG. 2 are printed on an inside of a posterior portion of the shirt and, and the patterns shown in FIG. 1 are printed on an inside of an anterior portion of the shirt. No particular color is claimed.

The patterns shown in FIGS. 1 and 2 include fingerprint-like patterns. The fingerprint-like patterns are shown in more detail in the zoomed-in views of FIGS. 3 and 4. Black lines in the patterns shown in FIGS. 3 and 4 have contrast in material and/or appearance with areas that are not shown in black (e.g., areas between two adjacent black lines). No particular color is claimed.
